(57) CLAIM

We claim the ornamental design for a modular rack, as shown and described.

DESCRIPTION

FIG. 8 is a bottom plan view of the modular rack in accordance with an embodiment of the present disclosure. FIG. 9 is a front-right perspective view of the modular rack in accordance with yet another embodiment of the present disclosure.

FIG. 10 is a rear-left perspective view of the modular rack of FIG. 9.

FIG. 11 is a right elevation view of the modular rack of FIG. 9.

FIG. 12 is a rear elevation view of the modular rack of FIG. 9.

FIG. 13 is a left elevation view of the modular rack of FIG. 9.

FIG. 14 is a front elevation view of the modular rack of FIG. 9.

FIG. 15 is a top plan view of the modular rack of FIG. 9; and, FIG. 16 is a bottom plan view of the modular rack of FIG. 9.

The portions of the modular rack in broken lines are included for the purpose of illustrating environment and form no part of the claimed design.
